UNITED STATES PATENT OFFICE.

WILLIAM J. REGAN, OF WILKINSBURG, AND ENOCH GEORGE, JR., OF PITTSBURGH, PENNSYLVANIA, ASSIGNORS TO THE McCONWAY & TORLEY COMPANY, OF PITTSBURGH, PENNSYLVANIA, A CORPORATION OF PENNSYLVANIA.

RAILWAY DRAFT APPLIANCE.

Application filed September 12, 1923. Serial No. 662,266.

To all whom it may concern:

Be it known that we, WILLIAM J. REGAN and ENOCH GEORGE, Jr., citizens of the United States, residing, respectively, at 5 Wilkinsburg, in the county of Allegheny and State of Pennsylvania, and Pittsburgh, in the county of Allegheny, State of Pennsylvania, have invented certain new and useful Improvements in Railway Draft Appliances; and we do hereby declare the following to be a full, clear, and exact description of the invention, such as will enable others skilled in the art to which it appertains to make and use the same.

15 Our invention relates to railway draft appliances, and is particularly concerned with bushings constituting wearing surfaces or liners for the slots with which car couplers and yokes are commonly fashioned for the 20 reception of a connecting key. By the use of the bushings, which may be of varying thicknesses, a single coupler casting made for their application may be used in conjunction with the several sizes of keys now 25 employed for connecting draft members of railway draft appliances and, moreover, the bushings may be so fashioned as to afford means for shifting the position of the key longitudinally of the key receiving slot of 30 the draft member.

The principal object of the invention is to produce for the purposes indicated a bushing which is simple in form, readily removable so that it may be renewed with a minimum expenditure of labor, and which is provided with means for reliably maintaining it in assembled position in the slot of the draft member upon which it is mounted.

35 The principal feature of the invention, generally stated, consists in providing a draft member, having a key receiving slot therein, with a bushing which extends into the slot and is furnished with means formed thereon for maintaining it in assembled relation to said draft member, the said bushing being adapted to cause said key to be positioned nearer one end of said slot than the other.

40 A further feature of the invention consists in the combination with a draft member formed with a key receiving slot, of a split bushing mounted on the draft member and extending into the slot, the said

bushing being of increased thickness at one end and being adapted to be bent so as to 55 cause it to assume assembled position.

Another feature of the invention consists in the combination with a draft member having a key receiving slot, of a bushing mounted on said draft member and extending into said slot, the draft member being formed with an interior recess, and the bushing being adapted to be bent and being provided with a projection adapted to enter said recess to maintain said bushing in 65 assembled position.

Other features of the invention relating to advantageous details of construction will hereinafter appear.

In the drawings illustrating a preferred 70 embodiment of the invention, the scope whereof is pointed out in the claims,—

Figure 1 is a vertical sectional view of the rear end of a car coupler and associated bushing embodying the invention.

Figure 2 is a sectional view on the line 2—2, Fig. 1.

Figure 3 is a detail plan view of the bushing.

Figure 4 is a side elevation of the bushing, showing it as bent to permit it to be introduced into the slot of the car coupler.

Figure 5 is a view corresponding to Fig. 1 but illustrating a modified form of the invention.

Figure 6 is a sectional view on the line 6—6, Fig. 5.

Figure 7 is a vertical sectional view of a combined car coupler and bushing, the forward portion of the coupler being broken 90 away and the position of the bushing when being assembled with the coupler being illustrated in dotted lines.

Figure 8 is a sectional view on the line 8—8, Fig. 7.

Figure 9 is a side elevation of the portion of the coupler shown in Figs. 7 and 8, but illustrating a slightly modified form of the bushing.

Figure 10 is a plan view of the rear end of a car coupler having key slots intersecting at right angles, showing the application to one of the slots of a bushing embodying the invention.

Figure 11 is a side elevation of the rear 105 end of the car coupler illustrated in Fig.

10 but illustrating the application of a bushing embodying the invention to the other slot of said coupler.

Figure 12 is a plan view of the rear end 5 of a car coupler having combined therewith in accordance with the invention another form of bushing.

Figure 13 is a vertical sectional view of the construction illustrated in Fig. 12.

10 Figure 14 is a plan view of the bushing shown in Figs. 12 and 13.

Figure 15 is a detail sectional view of a portion of the car coupler and associated bushing illustrating another modification of 15 the invention.

The railway draft appliance with which the invention is concerned is of the well known type involving slotted draft members, such as a car coupler and draft yoke 20 or links, which are operatively connected by means of a key. The preferred forms of bushings illustrated in the drawings are especially well suited to form liners for the slots of car coupler elements of railway 25 draft rigging and, accordingly, their relation to various types of slotted couplers has been illustrated in the drawings.

In the form of the invention shown in Figs. 1 to 4, inclusive, 1 indicates a car 30 coupler having a key receiving slot 2 extending therethrough from side to side, the interior of the coupler stem being hollow so as to afford a recess 3 which is availed of for cooperating with parts of the bushing to 35 maintain said bushing in mounted position on the coupler.

The bushing 4 associated with the coupler 40 1 extends into the slot 2 of the latter and preferably constitutes a complete or continuous lining for relieving the coupler of the wear of the connecting key (not shown). One end of the bushing may be of increased 45 thickness as indicated at 5, so as to cause the connecting key to be positioned nearer one end of the slot, thereby enabling the location of the key longitudinally of the draft member to be modified as may be desired. Upon one side of the bushing is provided projecting means adapted to extend 50 into the interior recess 3 of the draft member so as to maintain said bushing in assembled position, the said means preferably consisting of a plurality of lugs or projections 6 each of which is adapted to engage one of the bounding walls of the said recess. The bushing 4 is preferably split closely adjacent to the projections 6, as indicated at 7, thus permitting the bushing, which is capable 55 of being bent and preferably is formed as a forging or of malleable iron, to be bent or deformed (see Figs. 1 and 4) so as to enable it to be entered in the slot 2 of the coupler. After having been entered in the key receiving slot of the draft member, the portion 60 of the bushing carrying the projections 65

6 is bent or forced into operative position so as to cause said projections to assume their assembled position within the interior recess 3 of the coupler, thereby maintaining said bushing in place. It will be perceived 70 that the construction is such that after the bushing has been subjected to wear after being first put into service, it may be reversed so as to bring new wearing surfaces into 75 operation.

The modified form of construction illustrated in Figs. 5 and 6 is generally similar to the construction heretofore described, except that the bushing 8 is open at the end opposite its thickened portion 5; and this 80 construction also differs from that shown in Figs. 1 to 4, inclusive, in that the projecting means provided on the bushing for entering the interior recess 3 of the coupler 1 to maintain the bushing in assembled position, are 85 constructed as a single lug or projection 9 instead of a plurality of separated lugs. Other details of construction shown in Figs. 5 and 6 being identical with those already described have been indicated by corresponding 90 reference characters.

The car coupler 10 shown in Figs. 7 and 8 is provided with a key receiving slot 11 within which is mounted a split bushing 12. This bushing is of uniform thickness 95 throughout and the usual connecting key associated therewith (not shown) is therefore caused to be positioned centrally of the slot in the coupler. The bushing 12 is preferably provided upon one side with a plurality of spaced projections 13 corresponding in form and function to the projections 6 of the bushing 4. This bushing also is adapted to be bent so as to cause its projections 13 to enter the interior recess 14 of 100 the coupler 10.

The form of bushing 15 illustrated in Fig. 9 is the same as that disclosed in Figs. 7 and 8 except that it is open at one end, corresponding in this respect to the construction 110 shown in Figs. 5 and 6. This bushing is assembled with the coupler 10 by bending the part thereof bearing the projections 13, in a manner heretofore described, as illustrated in dotted lines.

The car coupler 16 shown in Figs. 10 and 11 is of the type provided with two intersecting key receiving slots extending at right angles to each other, one of them, 17, being adapted to receive a vertically disposed connecting key and the other, 18, being for the reception of a horizontal key for attaching the coupler to a draft yoke or the like. A bushing may be mounted upon the coupler 16 so as to form a liner for either of these 120 slots, 17 and 18, depending upon whether the draft member associated with the coupler is attached thereto by means of a vertical key or by a horizontal one. Except for the 125 differences in configuration necessary to 130

enable them to conform to the respective slots 17 and 18, the bushings used in conjunction with this coupler may be the same in construction as the bushing 12 shown in Figs. 7 and 8 and heretofore described; and accordingly these bushings have been indicated on the drawings by the reference numeral 12 and the projections thereof have been similarly indicated by the reference character 13. When the bushing is assembled with the coupler 16 for cooperation with a vertical key, the projections 13 extend into the interior recess of the coupler constituted by the horizontal slot 18; whereas, when the bushing 12 forms a liner for the horizontal slot 18 its projections 13 extend into the slot 17 provided for the reception of a vertical key. In either case the projections 13 when bent to assembled position cooperate with the coupler 16 to maintain the bushing in place.

The car coupler 19 illustrated in Figs. 12 and 13 is formed with a horizontal key slot 20 and with oppositely disposed interior recesses 21 communicating therewith, said recesses preferably being of cylindrical form to accommodate a projection 22 on the bushing 23 forming a lining for the slot 20. The projection 22, which is slightly tapered or inclined upon one side as indicated at 24, for the purpose of enabling it readily to be forced to assembled position, may be assembled in the slot of the coupler in a plurality of positions, the projection 22 being received in one or the other of the recesses 21 as the case may be. This permits the bushing when worn to be turned to offer a new wearing surface to the connecting key. The bushing is preferably split closely adjacent to the projection 22, as indicated at 25, to permit it to be readily bent to a position allowing it to be entered in the slot 20 and its projection 22 to be easily forced into the cooperating recess 21.

Fig. 15 illustrates the slot 20 of the coupler 19 as being equipped with a bushing 26 identically like the bushing 23 except that it forms a lining extending only around the sides and one of the ends of the coupler slot. The bushing 26 is provided with projections 22 like those heretofore described which are adapted to extend into either of the recesses 21 of the coupler 19 for the purpose of maintaining said bushing in alternative assembled positions.

Any of the forms of bushings embodying the invention lend themselves to simple processes of manufacture, as will be appreciated and they may be readily combined with the slotted draft members with very small expenditure of labor without the use of special tools.

We claim:

1. In a railway draft appliance, the combination with a draft member having a slot

adapted to receive a key forming an element of the draft appliance, of a bushing mounted on said draft member and extending into the slot thereof, said bushing being adapted to cause said key to be positioned nearer one end of said slot than the other.

2. In a railway draft appliance, the combination with a draft member having a slot adapted to receive a key forming an element of the draft appliance, of a bushing mounted on said draft member and extending into the slot thereof, said bushing being provided with projecting means adapted to engage said draft member to maintain the bushing in assembled position and being adapted to cause said key to be positioned nearer one end of said slot than the other.

3. In a railway draft appliance, the combination with a draft member having a slot adapted to receive a key forming an element of the draft appliance, of a split bushing mounted on said draft member and extending into the slot thereof, said bushing being of increased thickness at one end, whereby said key may be positioned nearer one end of said slot than the other.

4. In a railway draft appliance, the combination with a draft member having a slot adapted to receive a key forming an element of the draft appliance, of a bushing mounted on said draft member and extending into the slot thereof, said bushing being split and adapted to form a liner substantially coextensive with the walls of said slot, and being formed of metal adapted to be bent and being thicker at one end than at the other, whereby said key may be positioned nearer one end of said slot than the other.

5. In a railway draft appliance, the combination with a draft member having a slot adapted to receive a key forming an element of the draft appliance, of a bushing mounted on said draft member and extending into the slot thereof, said bushing being adapted to cause said key to be positioned nearer one end of said slot than the other, said bushing being split and adapted to be bent and being provided with a projection adapted to enter an interior recess of said draft member so as to maintain said bushing in assembled position.

6. In a railway draft appliance, the combination with a draft member having a slot adapted to receive a key forming an element of the draft appliance, of a bushing mounted on said draft member and extending into the slot thereof, said bushing being provided with a plurality of projections adapted to enter an interior recess of said draft member, and said bushing being split and adapted to be bent so as to cause said projections to assume an assembled position within said recess.

7. In a railway draft appliance, the combi-

nation with a draft member having a slot adapted to receive a key forming an element of the draft appliance, of a split bushing mounted on said draft member and extending into the slot thereof, said bushing being adapted to be bent and being provided with a projection adapted to engage said draft member to maintain said bushing in assem-

bled position, and said bushing being thicker at one end than at the other so as to cause 10 said key to be positioned nearer one end of said slot.

In testimony whereof we affix our signatures.

WILLIAM J. REGAN.
ENOCH GEORGE, JR.
